POWER DRIVEN APPARATUS

Filed Nov. 26, 1926

UNITED STATES PATENT OFFICE

AUGUST WENNERBERG, OF CHICAGO, ILLINOIS, ASSIGNOR TO WESTERN ELECTRIC COMPANY, INCORPORATED, OF NEW YORK, N. Y., A CORPORATION OF NEW YORK

POWER-DRIVEN APPARATUS

Application filed November 26, 1926. Serial No. 150,871.

This invention relates to power driven apparatus, and more particularly to a frictionally driven power apparatus for operating reciprocating mechanisms, such as punch presses.

The object of this invention is to provide a friction drive for power driven mechanisms embodying means for readily varying the driving pressure to a predetermined and uniform amount between a driving member and a driven member, and for expeditiously engaging or disengaging the driving member with or from the driven member.

In accordance with the general features of this invention as applied to a punch press or dieing machine, there is provided a pair of friction drive rollers carried upon the extremities of a pair of pivotal levers and yieldably maintained in driving engagement with the periphery of the fly wheel of the press at a point below the axis thereof, the rollers being driven by sprockets and chains operatively connected to a drive shaft forming a common axial support for the levers. The driving pressure of both of the rollers upon the fly wheel is controlled through the medium of an adjustable spring operatively associated with the levers, other means being included for simultaneously engaging or disengaging the rollers from the fly wheel.

Other objects and advantages of this invention will more fully appear from the accompanying detailed description taken in connection with the accompanying drawings, in which

Fig. 1 is a side view of a punch press or dieing machine having a friction drive embodying features of this invention applied thereto;

Fig. 2 is an enlarged fragmentary detail view, partly in section, of the drive shown in Fig. 1, and

Fig. 3 is a plan view thereof with the fly wheel omitted.

Referring now to the drawings in detail, in which like reference numerals designate similar parts throughout the several views, and particularly to Fig. 1, the numeral 5 indicates a fly wheel fixed to a crank shaft 6 rotatably journaled upon a punch press frame 7. Oper-

atively connected to the crankshaft in a usual manner is a crank arm 8 pivotally connected at its lower end to a vertically reciprocating cross head 9, the latter being secured to four rods 10 in turn reciprocally carried upon the frame 7, two of the rods being illustrated in the drawings, the other two being hidden. The rods 10 extend upwardly from the top surface of the frame 7 and support a cross head or ram 13 on which a depending punch 14 is carried, the punch cooperating during the operation of the press in a well known manner with a die 15 supported upon the upper surface of the frame to form or blank material inserted therebetween.

The punch press illustrated in the drawings and to which the improved friction drive has been applied represents a large or heavy duty type, its base being mounted in a pit 17 formed below the level of a floor 18, with the upper portion of the press extending thereabove to bring the cooperating punch 14 and the die 15 within convenient reach of an attending operator. The lower peripheral surface of the fly wheel 5 is positioned within the pit 17 along with a friction drive mechanism operatively associated therewith and embodying the features of this invention, which will be presently described, the opening in the floor resulting from the pit 17 being covered by a metal grating 21 which extends closely around the upwardly projecting portions of the press above the floor 18.

The improved friction drive embodying the features of this invention will now be described. A driving motor 22 carried upon the base 16 and having a sprocket pinion 23 fixed to its armature shaft is connected to a sprocket wheel 24 attached to a rotary shaft 25 by a chain 26. The motor 22 is preferably adjustably mounted upon the base 16 in any well known manner to provide a desired tension upon the chain 26. One means for performing such adjustment is indicated at 29. Vertically disposed journals 30 fixed to the base 16 support the shaft 25 adjacent opposite ends thereof, the sprocket wheel 24 and a collar 31 attached to opposite ends of the shaft and abutting outer faces of the journals serve to prevent longitudinal displacement of the

shaft. A pair of pivotal levers 32 and 33 are mounted upon the shaft 25 intermediate its ends, the shaft forming a common axis therefor upon which the levers may turn independently of the rotation of the shaft. The outer end of each of the levers 32 and 33 is bifurcated and supports thereon a relatively stationary shaft 36 which spans the arms formed upon the lever. Freely mounted for rotation upon each of the shafts 36 is a friction roller 37 provided upon its peripheral face with a sleeve 38 composed of cork or other suitable friction material for engaging the periphery of the fly wheel 5, the rollers being centered with respect to the face of the latter. Secured to each of the rollers 37 but at opposite ends thereof as indicated in Fig. 3 is a sprocket wheel 39, each sprocket wheel being operatively connected to a sprocket wheel 40 fixed to the shaft 25 at opposite ends thereof adjacent the inner faces of the journals 30, as viewed in Fig. 3, by a chain 43. It will be apparent that upon causing the shaft 25 to rotate, for instance, in a clockwise direction, the friction rollers 37 through the hereinbefore described arrangement and the cooperating sprocket wheels 24, 39 and 40 and their interconnecting chains 43 will also rotate in the same direction.

To maintain the friction rollers in engagement with the fly wheel 5 with a predetermined uniform driving pressure, the following mechanism is provided. Referring particularly to Figs. 2 and 3, the levers 32 and 33 upon their inner axial portions and at each end thereof are provided with a pair of upwardly extending arms 44 and 45, respectively, the arms 44 and 45 upon opposite corresponding ends of the levers being directly opposite and spaced from each other. Pivottally mounted upon the upper end of the arm 44, which is bifurcated, is a screw threaded eye bolt 46, the threaded end thereof freely passing through an aperture provided in the arm 45. Surrounding the projecting end of the bolt 46 is a coiled compression spring 47 with opposite ends thereof disposed between a face of the arm 45 and a nut 50 threaded onto the bolt. It will be apparent that the levers 32 and 33 are thus yieldably connected together and by uniformly adjusting the nuts 50 associated with the bolts 46 the frictional driving pressure of each of the rollers 38 upon the periphery of the fly wheel 5 may be regulated to a uniform and predetermined degree, the compression of the springs 47 normally maintaining the rollers in driving engagement with the fly wheel.

The means provided for simultaneously engaging or disengaging the rollers 37 with or from the fly wheel 5 will now be described. Rotatably carried in bearings 51 formed upon the journals 30 directly above the shaft 25 and extending across the inner axial portions of the levers 32 and 33 and within the space

provided between the vertical arms 44 and 45 formed thereon is a cam shaft 52. The opposite inner faces of each of the arms 44 and 45 between which the shaft 52 extends are provided with notches or depressions 53, the purpose of which will be presently described. Fixed to the shaft 52 at each end thereof between each set of the oppositely formed depressions 53 in the arms 44 and 45 is a cam member 54, the cam members normally occupying the position shown in the drawings. Collars 55 fixed to the shaft 52 upon sides of the bearing 51 at one end of the shaft serve to prevent the longitudinal displacement of the latter and consequently the cam members 54 mounted thereon. A hand wheel 56 (Fig. 1) is rotatably journaled upon the press frame 7 above the floor 18 and is operatively connected to the shaft 52 by a plurality of sprocket wheels 57 and chains 58 whereby an operator may conveniently rotate the cam members 54, 90° from their normal position as shown in their operative position in which they will engage the opposite surfaces of the arms 44 and 45 within the depressions 53 thereof. The latter position of the cam members 54 will cause the levers 32 and 33 to be rocked counter-clockwise and clockwise, respectively, upon the shaft 25 and thus disengage the rollers 37 simultaneously from the fly wheel 5. Upon a reverse movement of the hand wheel 56 the rollers 37 will again engage the fly wheel 5. It will be apparent that the disengagement or engagement of the rollers 37 with the fly wheel 5 may be effected without disturbing the transmission of power from the motor 22 to the rollers 37 or the normal driving pressure between the rollers and the fly wheel as determined by the adjustment of the springs 47 as hereinbefore described.

The feature provided for engaging or disengaging the friction drive from the fly wheel is of considerable advantage when changing or aligning punches or dies, in which case it is desirable that the operator be able to turn the fly wheel slowly by hand.

It is believed that the operation of the friction drive embodying the features of this invention will be clearly evident from the foregoing detailed description thereof without a general description of its operation.

What is claimed is:

1. In a power driven apparatus, a fly wheel, a pair of friction drive members therefor, levers independently supporting the drive members and having opposing surfaces, adjustable means for maintaining the drive members in driving engagement with the fly wheel, and means operatively disposed between the opposing surfaces of the levers and adapted to simultaneously disengage the drive members from the fly wheel without disturbing the normal adjustment of the adjustable means.

2. In a power driven apparatus, a fly wheel, a pair of friction drive members therefor, levers for independently supporting the drive members having a common fixed pivot and having angularly disposed arms, an adjustably mounted spring interconnecting the angularly disposed arms of the levers for maintaining a uniform predetermined driving pressure between the members and the fly wheel, and means movable into association with the levers for rendering the spring inoperative.

3. In a power driven apparatus, a driven element, a plurality of friction drive members therefor, a plurality of pivoted members supporting the drive members, and means operatively associated with the pivoted members for simultaneously disengaging the drive members from the driven element and disassociated from the pivoted members when the drive members are in driving engagement with the driven element.

4. In a power driven apparatus, a fly wheel of a punch press, a pair of drive rollers normally engaging the periphery of the fly wheel, a pair of levers having a common pivot and supporting said rollers, angularly disposed arms fixed to said levers, resilient means urging the arms together to thereby cause the rollers to bear against the periphery of the fly wheel, and cam means for forcing said arms apart to disengage the rollers from the fly wheel.

5. In a power driven apparatus, a fly wheel, a pair of driven rollers normally engaging the periphery of the fly wheel, a pair of levers supporting said rollers, angularly disposed arms fixed to said levers and having cam faces disposed adjacent each other, yielding means urging said arms together to thereby cause the rollers to bear on the periphery of the fly wheel, and a cam member adapted to co-act with said cam faces to force said arms apart and thereby disengage the rollers from the fly wheel.

6. In a power driven apparatus, a driven member, a plurality of friction drive members therefor, a plurality of pivoted members supporting the drive members, a plurality of arms fixed to said pivoted members and having faces disposed adjacent each other, yielding means urging said arms together to thereby cause the drive members to bear against the driven member, and cam means adapted to cooperate with said faces to disengage the drive members from the driven member.

In witness whereof, I hereunto subscribe my name this 12 day of November, A. D., 1926.

AUGUST WENNERBERG.
